UNITED STATES PATENT OFFICE

SAMUEL COHN, OF NEW YORK, N. Y.

METHOD AND APPARATUS FOR HANDLING TUBULAR TEXTILE FABRIC

Application filed March 7, 1929. Serial No. 345,180.

This invention relates to the handling of tubular textile fabric, either woven or knitted, and particularly to a method and apparatus whereby handling is facilitated and the 5 quality and other characteristics of the fabric are improved. While it is adapted for use in the treatment of silk, cotton or wool fabrics in tubular form, the invention is especially applicable to the handling of knitted rayon, 10 the latter fabric being unusually fragile when saturated with liquid and subject to shrinkage or deformation.

In handling fabrics after dyeing, it has been the universal practice to treat the fabric 15 in rope form or to spread it roughly by hand. Thus it is usual to remove water in centrifugals and to dry the fabric without attempting to remove the wrinkles. The fabric is conveyed in a "rough dry" condition to the finishing 20 machine where it is steamed and mangled to give it a commercial finish. The several operations involve repeated handling of the goods in a wet or moist condition with the consequent possibility of defacing or distorting 25 it.

An even more important factor in the handling of fabrics is the loss due to shrinkage which is especially marked in knitted rayon. The shrinkage loss in finishing is indefinite in 30 amount, and no method of controlling it has been available.

Shrinkage affects the width as well as the length of the goods. This is particularly true of tubular fabrics and is at the same time especially objectionable because such fabrics are generally made into garments which, of course, cannot be properly cut if the fabric does not conform to standards of width.

Another difficulty in the handling of fabrics arises from the fact that after removal of the major part of the water, they are frequently rolled or folded in a moist condition and held for periods of one to twenty-four hours before drying. This is necessary because drying is a slower operation than dehydration in centrifugals and similar apparatus. When goods are stored in a moist condition, even temporarily, the edges or other exposed portions dry out and oxidation or 45 other change may affect the dye at the exposed

portions of the fabric. The result is streaks or discoloration which cannot be removed.

Furthermore the ordinary treatment to which fabrics are subjected prior to finishing reduces the ultimate strength of the fibres of 55 which they are composed. The uneven stresses to which the fabric is subjected distort it and often cause serious defects therein. The repeated handling increases the chances of soiling and tearing the fabric. It involves 60 also a very considerable labor cost, much of which is unnecessary.

These and other disadvantages are the unavoidable result of a procedure which is ill adapted to the character of the material treated 65 and which has survived because the improved method and apparatus hereinafter described have not been available.

It is the primary object of the present invention to provide a method and apparatus 70 which avoid the difficulties and disadvantages of the procedure heretofore followed and especially to simplify and reduce the labor costs incident to the treatment of fabrics, to overcome shrinkage both lateral 75 and longitudinal, to strengthen the fabric, to prevent soiling and deformation and to permit storage of the fabric in a moist condition without danger of discoloration owing to premature drying of the exposed edges. 80

It is characteristic of most fibres that shrinkage of fabric made therefrom occurs when the fabric is dried after saturation with water. For the purpose of the present invention the fabric is regarded as wet or saturated if it contains approximately 25% or more by weight of water based upon the dry weight of the fabric. The fibres are ductile, and I have discovered if the fabric is stretched while wet and subjected in that condition to heavy pressure the fibres are definitely elongated and permanently fixed so that if the fabric is again saturated and dried no substantial shrinkage occurs. It is possible consequently to secure higher yields in 85 terms of yardage per pound of fibre used. Thus I am able to treat fabrics and to deliver to the consumer a yardage greater than has been possible with methods heretofore in use. 90

The same advantage is obtained with re- 100

spect to the width of the fabric since it may be stretched also in the transverse direction. The fabric may be given, therefore, a definite width which will not be altered subsequently 5 to any substantial extent even by repeated saturation and drying. The original sizes of garments made from the fabric will be retained, therefore, throughout the life of the fabric.

10 Since wet fabrics and especially knitted rayon fabrics are extremely delicate, the stretching of the fabric and the tension to which it is subjected for that purpose must be carefully determined and controlled. The 15 tension must be applied uniformly to all portions of the fabric. This is a matter of considerable difficulty in the case of tubular fabrics and consequently it has not been possible heretofore to subject fabrics of this class 20 to uniform tension and stretching.

I have overcome the difficulty by propelling the fabric by rolling contact with the major portion thereof so that the fabric advances evenly and without subjecting any part to 25 stress which would tear or distort it. In fact, the movement is so uniform that the wales in knitted fabric are maintained parallel and straight.

30 This is accomplished by the application of a propeller hereinafter more fully described but embodying spaced rolls driven at a pre-determined rate and co-operating with a floating stretcher frame enclosed within the tubular fabric and having rolls which are 35 rotated by contact through the fabric with the spaced driven rolls. The tubular fabric is distended to the desired amount depending upon the initial and desired width by lateral adjustment of complementary parts of the 40 frame. Rollers, which are positively driven to afford a peripheral speed preferably slightly higher than that of the spaced driving rolls, co-operate with idler rolls outside the fabric at the lateral edges of the frame. 45 Hence both the top and bottom as well as the sides of the tubular fabric advance at the predetermined rate. The fabric is initially opened by a spreader which is sized in accordance with the width of fabric treated 50 and is interchangeable with spreaders of varying dimensions to co-operate properly with the propeller. The spreader offers substantially no resistance to the fabric, friction being easily overcome by the uniform pull of 55 the propeller.

The fabric thus fed or propelled at a uniform rate may be subjected to various operations, but in the present instance I am more particularly concerned with the removal of 60 most of the water. For this purpose I employ, preferably, wringer rolls having a hard surface. The hardness should be such as to prevent substantial deformation of the rolls under the pressure of heavy springs.

65 It has not been practicable heretofore to

employ hard rolls with heavy pressure in wringers employed in removing water from delicate fabrics because any wrinkle in the fabric, presenting a plurality of thicknesses, would cause the fabric to be cut or weakened. Soft rolls, such as are customarily 70 used in wringers, do not remove sufficient water, hence the use of centrifugals.

If, however, the fabric is fed or propelled in a distended condition and under tension 75 to the wringer, all wrinkles are avoided. The fabric is absolutely flat and can be subjected to any desired degree of pressure between the hard rolls. In fact, heavy pressure is desirable 80 since it fixes or sets the fabric in its stretched condition and actually strengthens the fibres and the fabric. At the same time, the wringer removes a large proportion of the water and prevents the formation of moiré effects and other discolorations which result from the 85 uneven elimination of soapy water under the ordinary treatment heretofore employed.

To effect the stretching of the fabric in the direction of its length a suitable tension is maintained in the fabric between the propeller and the wringer rollers. The tension is maintained by a differential in speed of the fabric at the rolls of the propeller and wringer. This is effected by driving the wringer rolls to give the fabric a definite 90 linear speed at the bight of the rolls and by similarly driving the rolls of the propeller so that the fabric is fed at slightly lower speed. The tension must be varied depending upon the particular fabric which is 95 treated and should be adjusted to give the required stretch to the fabric. Provision may be made, therefore, to vary the speed of the propeller rolls, for example. Thus any desired differential may be maintained 100 with a corresponding longitudinal tension on the fabric.

The fabric which is positively fed by the propeller in a distended condition is brought to the wringer under tension with the two 110 opposite layers in contact and the double thickness of fabric passes between the wringer rolls, is subjected to pressure and is substantially freed from water. Because of the tension on the fabric as it enters the wringer rolls, it is impossible for any wrinkle to form in either the upper or lower layer. The fabric cannot be injured, therefore, by the application of heavy pressure by the hard surface 115 of the rolls. The fabric leaves the wringer as a flattened tube, flat and free from wrinkles and quite dry. It may be folded or preferably rolled on a mandrel and thereafter subjected to further treatment to dry and finish the fabric, or it may be delivered directly to 120 the drying or finishing machine.

If the fabric is rolled or folded in a damp condition to await further treatment, difficulty might result from premature drying of the edges. This is avoided readily, however, 125

5 by slightly crowning one or both of the wringer rolls. Thus the pressure on the fabric at the center is slightly greater than at the edges and the pressure may be adjusted so as to leave at the edges a slight surplus of moisture. Thus if the roll of fabric stands for a period of twenty-four hours or even more the edges will remain sufficiently moist to prevent discoloration by premature drying. 10 The amount of crowning necessary to accomplish my purpose is very slight and is greatly exaggerated in the accompanying drawing for the purpose of illustration. A difference in diameter between the center and 15 ends of the wringer rolls of a few thousandths of an inch is sufficient to accomplish the purpose of this invention.

Alternatively I may employ rollers of uniform diameter or other suitable means to 20 extract the water from the fabric, the edges of which are moistened before or after the fabric is rolled on the mandrel. The surplus water in the edges of the fabric prevents premature drying. Oxidation or staining is thus avoided. 25

It will be understood that the fabric in rope form from the dye vats or other treating apparatus can, in a single operation, be substantially freed from water, the water being 30 removed so as to leave no marks or discolorations, smoothed and wound, if desired, on a mandrel which facilitates the subsequent handling. At the same time, the fabric is stretched both laterally and longitudinally. 35 The fabric acquires a permanent set in the dimensions to which it is stretched and those dimensions are not affected to any substantial degree by any subsequent treatment of the fabric.

40 While the invention as herein set forth is concerned primarily with the removal of water, the principles may be applied to other operations. Thus the propeller or a plurality of propellers may be employed to feed the fabric over suitable drying frames whereon the fabric is subjected to hot air or other drying medium. Similarly the fabric may be propelled and fed to heated rolls and subjected intermediately to steaming. The 45 heated rolls iron and finish the fabric. It may be wound directly on a mandrel.

Throughout the treatment of the fabric after it leaves the wringer rolls it may be wound in rolls so that only the edges and 50 outside layer are exposed. These may be protected easily and since there is no necessity for the operator to touch the fabric, the possibility of soiling it is nullified.

The procedure in fact affords a marked 55 saving in material and in labor and assures the production of a product of the highest quality at the minimum cost. The saving accomplished by stretching the fabric is particularly marked and when considered in relation to the high value of the fabric and the

enormous yardage produced this advantage alone is sufficient to ensure the replacement of methods heretofore in use.

The method of this invention is not restricted to any particular apparatus. Nevertheless I have illustrated in the accompanying drawing an embodiment of the invention in a machine which is adapted to accomplish the various objects.

In the drawing,

Fig. 1 is a longitudinal section through a machine embodying my invention in the preferred form,

Fig. 2 is a plan view of the machine,

Fig. 3 is a detail in section of the mechanism for changing the speed of the propeller,

Fig. 4 is a section on the line 4—4 of Fig. 3,

Fig. 5 is a front elevation of the machine,

Fig. 6 is a plan view of the propeller showing the head in contracted form for relatively narrow fabric,

Fig. 7 is a similar view showing the propeller extended to correspond with a much wider fabric,

Fig. 8 is a sectional view taken on the line 8—8 of Fig. 7,

Fig. 9 is a perspective view of a portion of the stretcher,

Fig. 10 is a detail in perspective of a portion of the propeller frame,

Fig. 11 is an elevation of the crowned wringer rollers,

Fig. 12 is a detail view showing in elevation the device for carrying forward the leading edge of the fabric into the bight of the rollers,

Fig. 13 is a similar view of the same parts in a position to guide the fabric into the bight of the rollers,

Fig. 14 is a view similar to Figs. 12 and 13 showing another position of the parts,

Fig. 15 is a perspective view of one of the side members for carrying forward the leading edge of the fabric,

Fig. 16 is a detail in section showing the latch, and

Fig. 17 is a sectional view of the wind-up roller.

Referring to the drawing, the machine rests on a base 1. It includes a frame consisting of supports 2 and 3 which are connected by beams 4. Brackets 5 are supported on the frame and a roller 6 is journaled in the brackets and serves as a support for the spreading bar hereinafter described. A ring 7 on a bracket 8 guides the material into the machine. A pair of rollers 9 in parallel spaced relation are supported by shafts 10 which are journaled in the frame. These rollers co-operate with the propeller as hereinafter described.

The machine is driven through a belt 11 or other suitable driving connection from any source of power. The belt engages a pulley 12 on a shaft 13 carrying a sprocket 14. A chain 15 connects the sprocket 14 to a sprocket

16 on a shaft 17 journaled in the frame of the machine. A sprocket 18 on the shaft 17 is connected by a chain 19 to a sprocket 20 on a stub shaft 21. The latter shaft carries a gear 22 which meshes with a pinion 23 mounted on a stud 24 which is movable in a slot 25 of an arm 26 pivoted on the shaft 21. The arm 26 is provided with a handle 27 and is slotted at 28 to receive a bolt 29 secured in the frame of the machine. Thus the arm may be locked in any desired position, and when released may be moved by the operator to disengage the pinion 23 from a gear 30 on the lower shaft 10. The shafts 10 carry meshing gears 31 so that they rotate in opposite directions at the same peripheral speed. The gear 30 is removable and a gear having a different number of teeth may be substituted to afford a modified driving ratio. Thus the peripheral speed of the rollers 9 may be varied at will to afford the desired tension in the fabric.

The propeller, which is the device for holding and propelling the fabric in a distended or stretched condition, is disposed within the tubular fabric. As illustrated more particularly in Figs. 5 to 7 inclusive of the drawing, the propeller includes a frame consisting of end bars or plates 32 to which longitudinal bars 32' are secured, these bars extending inwardly toward the central portion of the propeller and overlapping so that the end bars or plates 32 may be moved toward and from each other to contract or expand the propeller. Two rollers 33 are mounted on each of the end plates 32 to drive the tubular fabric which is distended over the propeller, and stripper bars 34 are provided at the ends of the propeller to avoid entangling the fabric in the mechanism.

Four transverse rollers are supported in the propeller, the rollers being composed respectively of sections 35 and 36 having short shafts 37 journaled at their outer ends in the end plates 32. The inner ends of the shafts 37 are journaled in plates 38. A rod 39 on one of the end plates 32 telescopes within a tube 40 on the other end plate and a compression spring 41 surrounds the tube 40 and rod and tends to spread the end plates as indicated in Fig. 7. In Fig. 5, the propeller is illustrated in its contracted position corresponding to the smallest size of tubular fabric which may be treated in the machine. In this position the ends of the several sections 35 and 36 of the transverse rollers are contiguous, and the bars 32' of the frame overlap to a considerable extent. In Fig. 7 the propeller is expanded so that the sections 35 and 36 of the several transverse rollers are spread apart with their opposed ends separated.

The end rollers 33 are connected to and adapted to be driven from the sections 35 and 36 of the transverse rollers through bevel

gears 42 connecting the shafts of the several rollers. Thus when the transverse rollers are driven by co-operation with the rollers 9 the end rollers 33 are likewise driven at a uniform and predetermined peripheral speed to propel the fabric without distorting or subjecting it to uneven strains. It is desirable that the peripheral speed of the end rollers 33 slightly exceed that of the transverse rollers, and the gear ratio may be such as to effect this result. Lagging and possible distortion of the fabric at the edges is thus avoided.

The fabric 43 as it approaches the propeller passes over a wire frame 44 which opens the fabric initially. The wire frame 44 is bent to a U-shape and the ends are turned and inserted in apertures in a cross bar 45. This cross bar is provided with circumferential grooves 46. The bar 45 is adapted to be inserted in sockets 47 of brackets 48 which engage the circumferential grooves 46. The bar 45 holds the frame 44 in proper alignment with the sections 35 and 36 of the transverse rollers. If the fabric is to be expanded to a 20" width for example, the spread of the wire frame will correspond to this width and the grooves 46 in the bar 45 will be so positioned that when they are engaged in the brackets 48 the frame of the propeller will be locked against expansion and contraction. The propeller will be adjusted then so as to distend the fabric to the desired extent, that is to say, so that the fabric when flattened will have a width of 20". If a wider fabric is to be treated, the wire frame is removed and another of proper size is substituted. The latter will have grooves 46 adapted to lock the sections of the propeller in a new position which will ensure distension of the fabric to the required size.

On parallel rods 49 mounted between the frame members of the machine I provide two traveling blocks 50 and 51 each with a central opening to receive a threaded shaft 52 which is journaled in the frame of the machine and is provided at one end with a hand wheel 53. This shaft is provided at one end with a right-hand thread 54 and at the other with a left-hand thread 55, the openings in the respective blocks 50 and 51 having corresponding internal threads. Upwardly extending rods 56 on each of the blocks 50 and 51 carry idle rollers 57 which are adapted to press the fabric against the end rollers 33 of the propeller to ensure sufficient traction so that the sides of the fabric are propelled positively and uniformly and at a uniform speed with the remainder of the fabric. By operating the hand wheel 53 to revolve the threaded shaft 52 the blocks 50 and 51 may be moved toward each other to bring the idle rollers 57 into operative relation with the end rollers 33 of the propeller.

peller. When the hand wheel is turned in the opposite direction, the blocks 50 and 51 are moved apart to separate them from the end rollers 33 so that the fabric may be placed about the propeller.

5 After passing over the propeller the fabric engages guide rollers 58 which are mounted on arms 59 attached by brackets 60 to the longitudinal bars 32' at the delivery end of the propeller. These guide rollers 58 hold the fabric distended in the form of a flattened tube and guide it in this condition up to a point close to the bight of the wringer rollers hereinafter described. The guide rollers 58 do not come into contact with the wringer rollers and do not, therefore, injure the fabric.

10 The wringer rollers 61 are supported in brackets 62 attached to the side frame of the machine. The upper roller is driven by the shaft 17, and gears 61' connect the rollers so that they are both positively driven. The upper roller is adapted to be pressed downwardly by means of screws 63 which engage 15 springs 64, the latter resting in the bearing blocks of the upper wringer rollers. Thus the pressure of the wringer rollers may be adjusted by turning hand wheels 65 on the screws 63. The springs are sufficiently heavy 20 to exert a considerable pressure upon the fabric as it passes through the wringer rolls to ensure the maximum removal of water 25 from the fabric. I prefer to employ a spring pressure of from 1000 to 3000 pounds at each 30 bearing.

35 The wringer rollers may be made of any suitable material, but for the purpose of the present invention I prefer to employ hard rubber, that is to say rubber vulcanized to the point at which it will exert a substantially non-yielding pressure. Rubber having a hardness indicated by a durometer reading of from 90 to 100, preferably 98 or 99, is best adapted to accomplish the object of the 40 invention. Such rollers are contrasted with the ordinary soft rubber rollers which are employed ordinarily in wringers. They are adapted to apply high pressure to the fabric under the influence of the heavy springs 64 45 and thus to remove the maximum amount of moisture from the fabric. As hereinbefore indicated, it is possible to utilize such hard rubber rollers because the fabric is delivered to the wringer rollers in a flattened condition and free from wrinkles. The fabric cannot be cut, therefore, or otherwise injured 50 by the application of the heavy pressure.

55 Instead of being cylindrical, the wringer rollers may be crowned, that is to say they are made slightly larger at the middle portions and are tapered at each end so that when these rollers are in contact with each other they touch at their middle portions 60 and are in very slight contact or slightly

spaced at the ends. The amount of crowning may be very slight, that is to say the diameter of the ends may be only a few thousandths of an inch less than the diameter of the middle. I prefer to crown both rollers, 70 but the object of the invention can be attained by employing one crowned roller co-operating with a cylindrical roller. In Fig. 11 of the drawing the crowning is greatly exaggerated for the purpose of illustration.

75 The crowning of the rollers or of one of them is such that when the rollers acting under pressure press the flattened tubular fabric between them to extract water, the extraction will not be uniform over the full width of the fabric. There will be a greater percentage of moisture removed from the central portion of the fabric than from the side portions. Thus the residual moisture at the sides of the fabric will be greater than 80 at the middle. This ensures that when the fabric is rolled and stored temporarily the ends will not dry quickly and consequently there will be no discoloration of the fabric 85 at the exposed edges.

90 In the apparatus as so far described, the fabric 43 is distended over the propeller, is propelled thereby toward the wringer rollers, and is engaged by the wringer rollers and subjected to pressure for the purpose of removing water. The fabric is stretched laterally and is maintained in a stretched condition by the rollers 58 until it enters the bight of the wringer rollers. An important feature of the invention is that the fabric is 95 subjected to longitudinal as well as lateral tension between the propeller and the wringer rollers. It is engaged positively by both the propeller and the wringer rollers and cannot slip. Consequently it is possible to maintain a definite tension on the fabric and thus 100 to stretch it to the desired extent.

105 The stretching is accomplished by differential linear speed of the fabric at the propeller and at the wringer rollers. This differential is maintained by synchronizing the peripheral speed of the rollers of the propeller and wringer. Thus, for example, if the propeller is set to propel the fabric at a linear speed of 29 yards per minute and the wringer rollers are set to propel the fabric at a linear speed of 30 yards per minute, the fabric will be stretched accordingly and uniformly while it is in a wet or saturated condition. It will also be held 110 distended to a uniform width until the moisture is extracted by the wringer rollers.

115 The pressure exerted upon the fabric between the wringer rollers to extract a large percentage of the moisture while the fabric is under tension fixes or sets the position of each stitch in the fabric, and this position will be permanent, that is to say, after the treatment, whenever the fabric is free the 120 stitches will be uniform throughout. By 125 130

regulating the tension on the fabric while it is in the moistened condition and by extracting the moisture while it is still held under lateral and longitudinal tension it is possible 5 to set the tension between the several stitches so that the tube when it emerges from the machine will have a greater or less yield as desired, that is to say, a definite number of yards per pound within certain physical 10 limits of the fabric.

The stretching effected between the spreading device and the wringer rollers is possible because of the physical property inherent in every fibre to a greater or less degree called 15 ductility. Tension between the propeller and the wringer rollers results in elongation of the fibres. The fabric stretched and elongated while wet passes into the wringer rollers. Because of the flat and attenuated 20 condition of the fabric, the great pressure exerted by the hard rollers, and the simultaneous removal of the greater part of the water, the condition of the fibres composing the fabric is set and the fibres remain in their 25 new and extended relation throughout all subsequent treatment of the fabric.

The result is that shrinkage is decreased to a minimum. The elasticity of the fibre is reduced because of the elongation, and the 30 ability of the fibre to return to its original normal length is decreased to an extent which substantially avoids subsequent shrinkage.

The elongation effected is variable and can be induced to a greater or less degree, depending 35 upon the type of fibre and the amount of stretching desired. This permits control of yield. Yield means that for a definite width of a given cloth there is a given number of yards per pound. In the method described 40 the yield can be materially increased and it can be controlled so that a definite ratio of yardage, width and weight is possible.

It will be understood that in the practice 45 of the invention the amount of stretch to which the fabric is subjected will be varied depending upon the particular characteristics of the fabric. Consequently the peripheral speed of the propeller rolls will be adjusted 50 so as to feed the fabric at the required rate, that is to say at a linear speed proportionally lower than the linear speed of the fabric at the wringer rolls, thus providing the necessary differential in speed to effect 55 and maintain uniform stretching. When once adjusted for a fabric of given character, no further change need be made. In passing 60 through the machine every inch of the fabric is subjected to the uniform lateral and longitudinal stretching to accomplish the purpose described.

As an example of the application of the invention, a tubular rayon fabric was treated in the ordinary manner, i. e., the water was 65 removed in a centrifugal and the fabric was

dried. It measured 62 yards. This fabric was again saturated and passed through wringer rollers under tension as hereinbefore described. The fabric was then dried and measured 66 yards. The fabric was again 70 saturated and treated in the usual manner in a centrifugal and then dried. It still measured 66 yards, showing that the gain in yardage was permanent.

Another advantage of the invention is that 75 the stretching of the fibres actually increases the tensile strength thereof. Elasticity is reduced, but the fibres are stronger and the fabric is correspondingly less liable to damage through the breaking or tearing of the 80 threads. This is of special importance in connection with rayon fabrics because of the natural weakness of rayon fibre.

In the operation of the apparatus it is desirable to facilitate the introduction of the 85 fabric. Consequently I provide means for feeding the fabric from the propeller to the wringer rollers when the operation is initiated. For this purpose vertical supports 66 are disposed above the propeller and are provided with connecting blocks 67 at the top of which the feeding device is pivoted. The feeding device may consist of a shaft 68 journaled in extensions of the blocks 67. On this shaft are secured downwardly extending arms 69 arranged parallel with each other and in a vertical plane adjustable laterally on shaft 68. On the lower end of each of these arms there is a guiding member 70 pivoted on a bolt 71 to swing slightly in relation to the arm. The swinging movement is limited by a flange 71'. The member 70 is provided with a narrow blade 72 with a serrated edge 73.

The shaft 68, together with the arms 69, 100 is adapted to rock, and I have provided means which normally tend to move the arms 69 toward the wringer rollers. In the particular device illustrated, there is an arm 74 fixed to the shaft 68 and provided with a weight 75 which is on one side of the axis of the shaft, so that this weight tends to revolve the shaft 68 in a direction to cause the arms 69 to swing into the position shown in Fig. 13. A clip 76 on one of the arms 69 is adapted to engage a sleeve 77 on the upper shaft 10 (Fig. 12) to hold the arms 69 in retracted position. The fabric is threaded over the propeller, and the ends are slipped over the blades 72 and are caught on the 110 serrated edges 73. The machine is then started. Rotation of the shaft 10 disengages the clip 76 and permits the arms to advance with the fabric under the influence of the weight 75. The blades 72 enter the bight of the wringer rolls as indicated in Fig. 13, carrying the end of the fabric which is immediately gripped. The rollers 57 are moved then into contact with the fabric at the propeller. 125

As soon as the fabric is engaged by the wringer rollers, the operator may withdraw the blades 72 by swinging the arms 69 rearwardly to the position indicated in Fig. 14. 5 A projection 69' on one of the arms 69 engages a latch 70' which is pivotally mounted on one of the vertical supports 66 and provided with a handle 71'. The latch is moved out of operative position before the arms 69 advance 10 and is then moved into position by the operator to engage and hold the arms 69 in retracted position until a new piece of fabric is introduced to the machine. The arms are then retracted to engage the clip 76 with the 15 sleeve 77 and the feeding operation is repeated.

It is also desirable to facilitate the winding of the fabric as it comes from the wringer rollers. For that purpose an endless belt 78 20 travels around pulleys 79 and 80, the upper run of this belt being positioned to receive the fabric as it leaves the wringer rollers and to convey it to the winding roller. The pulley 79 is driven through a sprocket 79' and chain 25 81 from a sprocket 82 on the shaft 17. A roller 83 is provided with trunnions 84 which are adapted to engage the inclined surface of supports 85. When this roller is in its lowest position it rests against the belt 78 30 adjacent the rear pulley 80 and as the fabric is wound on the roller 83 the trunnions 84 rise up along the inclined surface of the supports 85. The roller 83 is provided with means for automatically engaging the leading 35 edge of the fabric to carry it around the roller. In the present embodiment the roller is provided with grooves 86 in which are mounted circumferential strips 87 of cloth provided with closely arranged pins 88 projecting outwardly therefrom. The ends of 40 the pins 88 project slightly beyond the periphery of the roller 83 as shown in Fig. 17.

As the leading edge of the fabric leaves the wringer rollers it is guided by a lip 80' on to the belt 78 and the latter carries it along until the end is touched by the revolving winding roller 83, this roller being revolved by the belt 78 with which it contacts. The several pins 88 will engage the end of the fabric and cause 45 the latter to be picked up automatically so that it travels around the roller and is wound upon itself in the form of a roll. Thus it is unnecessary for an attendant to stand at the delivery end of the machine and start the end of each strip of the fabric on the winding roller. The mechanism also avoids the folding 50 of the fabric at the starting end and saves a portion of the fabric which is ordinarily 55 rendered unsuitable for commercial use.

In the operation of the machine as described the operator first adjusts the propeller to distend the fabric to the required degree by introducing a stretching frame of the required size. The end of the fabric is then

slipped over the stretching frame and propeller. The side edges of the fabric are drawn forwardly and pass over the forward edges of the blades 72. The swinging arms 69 will be in the position shown in Fig. 1 and 70 will be held temporarily in this position by engagement of the clip 76 to overcome the tendency of the weight 75 to move the arms 69. The power is then applied and the propeller commences to operate and propel the 75 fabric. Simultaneously the leading edge of the fabric will be drawn by the arms 69 at a speed corresponding to that of the propeller. The flattened tube will pass over the guide rollers 58 and will be fed then into the bight 80 of the wringer rollers. The rollers 57 are then moved to engage the fabric. The wringer rollers will propel the fabric and the feeding device, having performed its function, is retracted and will remain inactive 85 until another strip of fabric is threaded through the machine. It will be observed that the blades 72 may pivot to a slight extent so that the sharp blades may project accurately into the bight of the wringer rollers. 90

As the fabric is propelled between the wringer rollers it passes onto the belt 78, and when the leading end reaches the roller 83 it is engaged thereby and is carried around the roller. Thereafter the fabric is wound in 95 the form of a roll.

The fabric is first opened by the frame 44 preparatory to its passage over the propeller. From there the fabric travels over the propeller which holds it distended or stretched, and at the same time it is propelled by rolling contact exerted both inside and outside the tubular fabric. The fabric then passes between the wringer rollers, being held in the form of a flattened tube, preparatory to its engagement by the wringer rollers by means of the spreading guide rollers 58. As the fabric passes from the wringer rollers, it travels with the upper run of the belt 78 and is automatically wound on the roller 83. 100 105

The method and apparatus herein described are applicable to the treatment of fabrics in tubular form. These may be knitted or woven fabrics. Woven fabrics are not generally tubular as they come from the looms, but such fabrics may be stitched in tubular form for treatment as described. After the fabrics are finished the stitching can be removed. The benefits of the invention are thus easily secured, regardless of the form in which the goods are originally fabricated. 110 115

Various changes may be made in the details of the procedure and in the apparatus employed without departing from the invention or sacrificing any of the advantages thereof. 120

I claim:

1. The method of treating tubular textile fabric which comprises subjecting it to regulated and uniform longitudinal tension while the fabric is wet and removing the 130

major portion of the water while the fabric is under tension.

2. The method of treating tubular textile fabric which comprises subjecting it to regulated and uniform longitudinal and transverse tension while the fabric is wet and removing the major portion of the water while the fabric is under tension.

3. The method of treating tubular textile fabric which comprises subjecting it to regulated and uniform longitudinal tension while the fabric is wet and removing the major portion of the water by pressure while the fabric is under tension.

4. The method of treating tubular textile fabric which comprises subjecting it to regulated and uniform longitudinal tension while the fabric is wet and removing the major portion of the water by rolling pressure while the fabric is under tension.

5. The method of treating tubular textile fabric which comprises subjecting it to regulated and uniform longitudinal and transverse tension while the fabric is wet and removing the major portion of the water by pressure while the fabric is under tension.

6. The method of treating tubular textile fabric which comprises stretching the fabric by regulated and uniform longitudinal tension while the fabric is wet and fixing the fabric in the stretched condition by pressure applied thereto while the fabric is under tension.

7. The method of treating tubular textile fabric which comprises stretching the fabric by regulated and uniform longitudinal and transverse tension while the fabric is wet and fixing the fabric in the stretched condition by pressure applied thereto while the fabric is under tension.

8. The method of treating tubular textile fabric which comprises propelling spaced transverse sections of the fabric positively at different linear speeds to maintain a uniform longitudinal tension in the fabric while it is wet and subjecting the fabric to pressure while under tension.

9. The method of treating tubular textile fabric which comprises propelling spaced transverse sections of the fabric positively at different linear speeds to maintain a uniform longitudinal tension in the fabric while it is wet and removing the major portion of the water by pressure while the fabric is under tension.

10. The method of treating tubular textile fabric which comprises distending the fabric while it is wet to predetermined transverse dimension, subjecting it to regulated and uniform longitudinal tension and removing the major portion of the water while the fabric is under tension.

11. The method of treating tubular textile fabric which comprises distending the fabric while it is wet to predetermined transverse

dimension, subjecting it to regulated and uniform longitudinal tension and removing the major portion of the water by pressure while the fabric is under tension.

12. The method of treating tubular textile fabric which comprises distending the fabric while it is wet to predetermined transverse dimension, subjecting it to regulated and uniform longitudinal tension and removing the major portion of the water by rolling pressure while the fabric is under tension.

13. The method of treating tubular textile fabric which comprises distending the fabric while it is wet to predetermined transverse dimension, propelling spaced transverse sections of the fabric positively at different linear speeds to maintain a uniform longitudinal tension and removing the major portion of the water by pressure while the fabric is under tension.

14. The method of treating tubular textile fabric which comprises distending the fabric while it is wet to predetermined transverse dimension, propelling the distended fabric positively, flattening the tubular fabric, propelling the flattened portion of the fabric at a speed slightly higher than that of the flattened portion to maintain a regulated and uniform longitudinal tension in the fabric and removing the major portion of the water while the fabric is under tension.

15. The method of treating tubular textile fabric which comprises subjecting it to regulated and uniform longitudinal tension while the fabric is wet and removing the major portion of the water by pressure while the fabric is under tension, the pressure being greater at the center than at the margins of the fabric so that the margins remain relatively moist.

16. The method of treating tubular textile fabric which comprises subjecting it to regulated and uniform longitudinal tension while the fabric is wet and removing the major portion of the water by rolling pressure while the fabric is under tension, the pressure being greater at the center than at the margins of the fabric so that the margins remain relatively moist.

17. The method of treating tubular textile fabric which comprises subjecting it to regulated and uniform longitudinal and transverse tension while the fabric is wet and removing the major portion of the water by pressure while the fabric is under tension, the pressure being greater at the center than at the margins of the fabric so that the margins remain relatively moist.

18. The method of treating tubular textile fabric which comprises propelling spaced transverse sections of the fabric positively at different linear speeds to maintain a uniform longitudinal tension in the fabric while it is wet and removing the major portion of the water by

water by pressure while the fabric is under tension, the pressure being greater at the center than at the margins of the fabric so that the margins remain relatively moist.

19. The method of treating tubular textile fabric which comprises distending the fabric while it is wet to predetermined transverse dimension, subjecting it to regulated and uniform longitudinal tension and removing the major portion of the water by pressure while the fabric is under tension, the pressure being greater at the center than at the margins of the fabric so that the margins remain relatively moist.

20. The method of treating wet tubular textile fabric which comprises removing a portion of the moisture from the fabric, leaving the edges relatively more moist than the body of the fabric, and winding the fabric with the moist edges exposed.

21. The method of treating wet tubular textile fabric which comprises winding the fabric with exposed edges relatively more moist than the body of the fabric.

22. The method of treating tubular textile fabric which comprises distending the fabric to predetermined transverse dimension and positively propelling the upper and lower runs and the lateral edges of the fabric, the speed at the edges being slightly in excess of the speed of the upper and lower runs.

23. The method of extracting moisture from tubular fabric which consists of positively propelling the fabric over a stretch-

25 ing and propelling head disposed within the traveling tube of fabric, and passing the tube of fabric between wringer rollers as it travels over said head, whereby the moisture is removed from the fabric by said wringer rollers, as it is distended by said head.

24. The method of extracting moisture from tubular fabric which consists of positively propelling the fabric, while wet, over a propelling head disposed within the traveling tube of fabric, said head being adapted to hold the tube of fabric in stretched condition, and passing the tube of fabric as it leaves said head between wringer rollers whereby moisture is removed from the stretched fabric by pressure exerted by said wringer rollers.

25. The method of extracting moisture from tubular fabric which consists of positively propelling the moist fabric over a propelling head lying within the traveling tube of fabric, said propelling head being adapted to hold the fabric in expanded condition while passing thereover, and passing the fabric in the form of a flattened tube between wringer rollers as it leaves said head, whereby the moisture is removed from the fabric by pressure exerted by said wringer rollers.

26. The method of extracting moisture from tubular fabric which consists of positively propelling the fabric over a stretching

and propelling head lying within the traveling tubular fabric, said propelling head being adapted to hold the tubular fabric expanded to a predetermined circumference and passing the tubular fabric in flattened condition in substantially the same circumferential dimensions as when the same is engaged by said propelling head, between wringer rollers which exert a rolling pressure on the flattened fabric, to extract the moisture therefrom.

27. A method of handling strips of tubular fabric which consists of passing the fabric between wringer rollers in which greater pressure is exerted on the middle portion of the strip of fabric than at the side portions thereof, and winding the fabric upon itself in the form of a roll, whereby the end portions of the roll contain a larger percentage of residual moisture than the central portion of the roll.

28. A machine for stretching and drying tubular fabric, comprising a propelling head having a frame carrying longitudinal and end rollers in relatively fixed relation adapted to lie within the tubular fabric while the latter travels thereover, other rollers external to the tubular fabric and co-operating with the rollers on the frame to propel the fabric continuously over said frame, and wringer rollers operating by rolling pressure on the tubular fabric as it travels over said propelling head, for pressing the moisture from the tubular fabric.

29. A machine for stretching and drying tubular fabric, comprising a propelling head having a frame carrying longitudinal and end rollers in relatively fixed relation adapted to lie within the tubular fabric while the latter travels thereover, and adapted to expand the fabric to a predetermined circumference, other rollers external to the fabric and co-operating with the rollers on the frame to propel the fabric continuously over said frame, means operating in advance of said first mentioned rollers for expanding the tubular fabric to a greater circumferential dimension than the dimension to which it is expanded by said first mentioned rollers, and wringer rollers operating by rolling pressure on the tubular fabric as it leaves said propelling head, for pressing the moisture from the tubular fabric.

30. A machine for stretching and drying tubular fabric, comprising a stretching and propelling head carrying longitudinal and end rollers in relatively fixed relation over which the tubular fabric is propelled and expanded, co-operating wringer rollers between which the fabric passes from said propelling head in the form of a flattened tube, and means attached to said propelling head for spreading the tubular fabric in the form of a flattened tube immediately in advance of said wringer rollers.

31. A machine for stretching and drying tubular fabric, comprising a spreading and propelling head carrying longitudinal and end rollers in relatively fixed relation over which the tubular fabric is adapted to be propelled with said head lying within the tubular fabric, co-operating wringer rollers operating to exert rolling pressure on the tubular fabric while in flattened condition as the same leaves said propelling head, and arms carried by said propelling head and extending to points adjacent said wringer rollers for spreading the tubular fabric in the form of a flattened tube immediately preceding its passage between said wringer rollers.

32. A device for removing moisture from tubular fabric by wringer action, comprising co-operating rollers adapted to press the fabric between them, at least one of said rollers being crowned, and so proportioned that a greater wringing pressure is exerted along the middle portion of the strip of fabric than the side portions thereof.

33. A device for removing moisture from fabric by wringer action, including co-operating rollers adapted to press the fabric between them, said rollers being crowned and so proportioned that the intermediate portion of the strip of fabric will be treated to a greater rolling pressure than the side portions thereof.

34. In a device of the class described, a propelling head adapted to lie inside a traveling tube of fabric, including a frame composed of telescoping sections adapted to be expanded and contracted, and having rollers thereon, rollers exterior of the fabric and co-operating with the rollers of said head to hold the head and to propel the fabric thereover, a frame for opening the fabric preparatory to its passage over said propelling head, and means on the frame of said propelling head with which said second mentioned frame co-operates to hold the frame of the propelling head in a predetermined position of adjustment.

35. In a device of the class described, a propelling head adapted to lie inside a tube of traveling fabric, and including a frame composed of telescoping sections adapted to be expanded and contracted, and having rollers thereon, rollers exterior of the fabric and co-operating with the rollers of said head to hold the head and propel the fabric thereover, engaging means on the sections of said frame, and a frame for opening the fabric preparatory to its passage over said head, said expanding frame being pivotally mounted on said engaging members of said propelling head frame and adapted to hold said latter frame in a predetermined position of adjustment.

36. In a device of the class described, a propelling head adapted to lie inside a tube

of traveling fabric, including a frame composed of sections adapted to be expanded and contracted, and having rollers thereon, rollers exterior of the fabric and co-operating with the rollers of said head to propel the fabric over said head, members on said frame members having sockets in the frame for opening the fabric preparatory to its passage over said head, said frame including a bar having peripheral grooves, the grooved portions of said bar being adapted to seat in said sockets whereby said bar holds the frame of the propelling head in predetermined position of adjustment.

37. In a device of the class described, means for propelling a strip of fabric, co-operating rollers to which the fabric is adapted to be fed, movable means for conducting the leading end of the fabric from said propelling means, and adapted to feed it into the bight of said rollers and means for automatically releasing the conducting means.

38. In a device of the class described, means for propelling a strip of fabric, co-operating rollers to which the fabric is adapted to be fed, movable feeding means or conducting the leading end of the fabric from said propelling means and adapted to feed it into the bight of said rollers, gravity means for moving said feeding means in the direction of motion of the fabric and means for automatically releasing the gravity means.

39. In a device of the class described, means for propelling a strip of fabric, cooperating rollers to which the fabric is adapted to be fed, movable feeding means for conducting the leading end of the fabric from said propelling means and adapted to be fed into the bight of said rollers, and means for moving said feeding means in the direction of motion of the fabric, said moving means being resistible whereby the movement of said feeding means is controlled by the speed of delivery of the fabric from said propelling means.

40. In a device of the class described, means for propelling a strip of fabric, co-operating rollers to which the fabric is adapted to be fed, movable feeding means for carrying the leading end of the fabric and for presenting it into the bight of said rollers, gravity means for moving said feeding means toward said rollers and means for automatically releasing the gravity means.

41. In a device of the class described, means for propelling a strip of fabric and co-operating rollers to which the fabric is adapted to be fed, means for conveying the leading end of the fabric and presenting it into the bight of said rollers, including members having sharp edges adapted to enter the bight of said rollers whereby the fabric will be automatically taken by said rollers and means for automatically releasing the conveying means.

42. In a device of the class described, means for propelling a strip of fabric, co-operating

- rollers to which the fabric is adapted to be fed, and means for carrying the leading end of the fabric from said propelling means and for feeding the same into the bight of said rollers, comprising movable means having fabric engaging members provided with sharp edges adapted to be projected into the bight of said rollers, said fabric engaging members being pivotally mounted on said movable means.
43. In a device of the class described, means for propelling a strip of fabric, co-operating rollers to which the fabric is adapted to be fed, and means for carrying the leading end of the fabric from said propelling means and for delivering it into the bight of said rollers, comprising a pivotal support, and members pivoted thereon and having sharp edges over which the fabric is adapted to be placed, said edges being adapted to guide the fabric into the bight of said rollers.
44. In a device of the class described, means for propelling a strip of fabric, co-operating rollers to which the fabric is adapted to be fed, and means for carrying the leading end of the fabric from said propelling means and to feed it into the bight of said rollers comprising a movable support, fabric engaging members disposed at the sides of the path of the fabric and having means to be engaged by the fabric, said fabric holding members being adapted to guide the fabric into the bight of said rollers.
45. In a device of the class described, a propelling head adapted to lie inside a tube of traveling fabric, means exterior of the fabric and co-operating with said head to hold the head in position and to propel the fabric thereover, co-operating rollers to which the fabric is fed from said propelling head, and means for conveying the leading end of the fabric from the propelling head into the bight of said rollers, including movable means with which the fabric is adapted to be engaged, said movable means being adapted to present the fabric into the bight of said rollers, whereby the propulsion of the fabric will be taken up thereby.
46. In a device of the class described, means for propelling a strip of fabric, co-operating rollers to which the fabric is adapted to be fed, and means for carrying the leading end of the fabric from said propelling means to said rollers, including movable means having fabric engaging members thereon with which the end of the fabric is adapted to be engaged, said fabric engaging members being disposed at the sides of the path of the fabric and adapted to guide the fabric into the bight of said rollers, the fabric being adapted to disengage from said fabric engaging members when its propulsion has been taken up by said rollers.
47. In a device of the class described, means for propelling a strip of fabric, co-operating rollers to receive the fabric from the propelling means, and means for guiding the leading end of the fabric from said propelling means to said rollers, comprising a movable support and means for urging said support to move in the direction of the movement of the fabric, and releasable means for holding said support positioned adjacent the propelling means, said support having fabric engaging members adapted to guide the fabric into the bight of said rollers.
48. In a device of the class described, means for propelling a strip of fabric, including revolvable means, rollers to receive the fabric from said propelling means, and means for feeding the leading end of the fabric from said propelling means into said rollers, comprising a movable support, and means for urging it in the direction of movement of the fabric, a resilient arm movable with said support, and a revolvable member operable with said propelling means, and engaging said arm to hold said support adjacent the propelling means, and adapted to release said arm upon the operation of said propelling means.
49. In a device of the class described, co-operating rollers to the bight of which fabric is adapted to be fed for the passage of the fabric between said rollers, movable means for conducting the leading end of the fabric and feeding it into the bight of said rollers, and means for automatically releasing the movable means.
50. A device for handling tubular fabric, including means adapted to lie inside of a tube of traveling fabric and including pairs of revolvable members, the members of each pair being relatively adjustable in the directions of their axes, and means exterior of the tubular fabric having revolvable means co-operating with the revolvable members inside the tubular fabric for supporting said interior means and propelling the fabric thereover, by positive inside and outside rolling pressure acting substantially throughout the circumference of the fabric.
51. A device for handling tubular fabric including means adapted to lie inside of a tube of traveling fabric and including a frame, revolvable members arranged in said frame in pairs, the members of each pair being relatively adjustable in the directions of their axes, and means exterior of the tubular fabric having revolvable means co-operating to engage the fabric between the interior and exterior revolvable means, said interior revolving means being operated by rolling action by said exterior revolving means.
52. A device for handling tubular fabric, including means adapted to lie inside of a tube of traveling fabric and including a frame, spaced, parallel revolvable rollers over which the fabric is adapted to travel mounted in said frame in pairs, the members of each

pair being relatively adjustable in the directions of their axes, and means exterior of the tubular fabric including a roller lying between and co-operating with said interior rollers to drive the latter and to prevent the travel of the interior means with the fabric, said exterior roller lying parallel with said interior roller.

53. A device for stretching tubular fabric, including means adapted to lie inside of a tube of traveling fabric and including a frame, revolvable members thereon arranged in pairs, the members of each pair being relatively adjustable in the directions of their axes and means exterior of the tubular fabric having revolvable means engaging with said interior revolving means for operating the latter to propel the fabric by rolling contact.

54. A device for handling tubular fabric, including means adapted to lie inside of a tube of traveling fabric and including a frame, upper and lower pairs of rollers mounted in said frame, the rollers of each pair being relatively adjustable in the directions of their axes, and means exterior of the tubular fabric having revolvable rollers engaging between the said upper and lower pairs of rollers and co-operating therewith to propel the fabric by rolling contact.

55. A device for handling tubular fabric, including means adapted to lie inside of a tube of traveling fabric and including a frame, longitudinal rollers thereon, end rollers on said frame adjacent the ends of said longitudinal rollers, and means exterior of the tubular fabric co-operating with said longitudinal rollers to propel the fabric over said interior device.

56. A device for handling tubular fabric, including means adapted to lie inside of a tube of traveling fabric and including a frame, longitudinal rollers thereon, end rollers disposed at right angles to said longitudinal rollers adjacent the outer ends of said longitudinal rollers, and means exterior of the tubular fabric co-operating with said longitudinal rollers to propel the fabric over said interior means.

57. A device for handling tubular fabric, including means adapted to lie inside of a tube of traveling fabric, including a frame, horizontally disposed rollers, end rollers disposed at right angles to and adjacent the outer ends of said longitudinal rollers and adapted to be driven by said longitudinal rollers, and means exterior of the tubular fabric, having revolvable means co-operating with said longitudinal rollers for propelling the fabric over said interior means.

58. A device for handling tubular fabric, including means adapted to lie inside a tube of traveling fabric, including a frame, longitudinal rollers journaled in said frame, means exterior of the tubular fabric and co-operating with said interior rollers for propelling

the fabric, end rollers on said interior device and means for propelling said end rollers whereby their peripheral speed will be greater than the peripheral speed of said longitudinal rollers.

59. A device for handling tubular fabric, including means adapted to lie inside a tube of traveling fabric, including a frame, longitudinal rollers on said frame, end rollers on said frame operated from said longitudinal rollers so that the peripheral speed of the ends rollers will be greater than the peripheral speed of the longitudinal rollers, and means exterior of the tubular fabric, including rollers cooperating with said longitudinal rollers to propel the fabric.

60. A device for handling tubular fabric, including means adapted to lie inside of a tube of traveling fabric and including a frame having revolvable members thereon and revolvable means exterior of the tubular fabric co-operating with the revolving members inside the tubular fabric for supporting said interior means and propelling the fabric thereover, the frame of said interior means comprising telescoping sections adapted to be expanded and contracted to adapt said device for stretching the fabric to different sizes.

61. A device for handling tubular fabric, including means adapted to lie inside a tube of traveling fabric and including a frame, a plurality of spaced, revolvable members, said frame comprising telescoping sections adapted to be expanded and contracted to adapt the device for stretching fabric to different sizes, and revolvable means exterior of the tubular fabric co-operating with the revolvable members inside the tubular fabric for supporting said interior means and propelling the fabric thereover.

62. A device for handling tubular fabric, including means adapted to lie inside of a tube of traveling fabric and including a frame comprising telescoping sections adapted to be expanded and contracted to adapt the device for stretching fabric to different sizes and having revolvable members thereon and revolvable means exterior of the tubular fabric co-operating to engage the fabric between the exterior and interior revolvable members, said interior revolvable members being operated by rolling action by said exterior revolving means.

63. A device for handling tubular fabric, including a frame adapted to lie inside a tube of traveling fabric, said frame comprising telescoping sections adapted to be expanded and contracted to adapt the device for stretching fabric to different sizes, parallel, revolvable rollers on said frame over which the fabric is adapted to travel, and means exterior of the tubular fabric including a roller lying between and co-operating with said interior rollers to drive the latter and to pre-

vent the travel of the interior means with the fabric, said exterior rollers lying parallel with said interior rollers.

64. A device for handling tubular fabric including means adapted to lie inside a tube of traveling fabric, including a frame, longitudinal rollers thereon, end rollers in relatively fixed relation and operatively connected to the longitudinal rollers and means exterior of the tubular fabric co-operating with said longitudinal rollers to propel the fabric over said interior device, said frame being adapted to be expanded and contracted to adapt the device for stretching fabric to different sizes.

65. A device for handling tubular fabric, including means adapted to lie inside a tube of traveling fabric, including a frame composed of expanding and contracting members, longitudinal rollers comprising sections mounted respectively on the members of the frame, end rollers on said frame disposed at right angles to said longitudinal rollers and adapted to be moved toward and from each other upon the adjustment of said frame, and means exterior of the tubular fabric and co-operating with said longitudinal rollers to propel the fabric over said interior means.

66. A device for handling tubular fabric, including a frame adapted to lie inside a tube of traveling fabric, said frame consisting of expanding and contracting sections, horizontally disposed rollers on said frame, end rollers on said frame disposed at right angles to said longitudinal rollers and means whereby said end rollers are driven by said longitudinal rollers, said end rollers being adapted to move toward and from each other with the frame sections, and revolvable means exterior of the tubular fabric co-operating with said longitudinal rollers for propelling the fabric over said interior means.

67. A device for handling tubular fabric, including a frame adapted to lie inside a tube of traveling fabric and including end plates and connecting members adapted to be expanded and contracted, longitudinal rollers journaled in said end plates, end rollers projecting beyond said end plates and arranged at right angles to said longitudinal rollers and adapted to be moved toward and from each other with the adjustment of the frame, means whereby said end rollers are operated from said longitudinal rollers, and means exterior of the tubular fabric co-operating with said longitudinal rollers to propel the fabric over said interior means.

68. A device for handling tubular fabric, including a frame adapted to lie inside a tube of traveling fabric, composed of sections adapted to be expanded and contracted, longitudinal rollers on said frame composed of sections adapted to move toward and from each other with the adjustment of said frame, and revolvable means lying outside the tube

of fabric and co-operating with said interior rollers to propel the fabric over said stretching device.

69. A device for handling tubular fabric, including a frame adapted to lie inside a tube of traveling fabric and composed of sections adapted to be expanded and contracted, parallel, longitudinal rollers on said frame composed of a plurality of sections arranged in axial alignment, said sections being adapted to be moved toward and from each other with the contraction and expansion of said frame members, and revolvable means exterior of the tubular fabric and co-operating with said interior rollers for propelling the fabric over said stretching device.

70. A device for handling tubular fabric, including a frame adapted to lie inside a tube of traveling fabric and composed of sections adapted to be expanded and contracted, longitudinal rollers mounted on said frame and composed of aligned sections adapted to be moved toward and from each other with the adjustment of said frame sections, and end rollers projecting from said frame and disposed at right angles to said longitudinal rollers and adapted to be moved toward and from each other with the adjustment of the frame sections, and revolvable means exterior of the fabric co-operating with said longitudinal rollers to propel the fabric over said stretching device.

71. A device for handling tubular fabric, including a propelling head carrying longitudinal and end rollers in relatively fixed relation adapted to lie inside a tube of traveling fabric, other rollers arranged outside the tube of fabric and co-operating with the rollers of said propelling head to propel the fabric over said head, co-operating rollers between which the flattened tube of fabric is adapted to be passed after traveling over said propelling head, and means mounted on said propelling head for distending the fabric into a flattened tube and for guiding the same adjacent said co-operating rollers.

72. A device for handling tubular fabric, including a propelling head adapted to lie inside a tube of traveling fabric, including a frame carrying longitudinal and end rollers in relatively fixed relation, other rollers arranged outside the tube of fabric, co-operating with the rollers of said head to propel the fabric over said head, pressing rollers adapted to press the flattened tube of fabric after it is passed over said propelling head, and means attached to said propelling head and lying inside the tube of fabric, adapted to distend the fabric in the form of a flattened tube and to guide the same adjacent said pressing rollers, said means being supported out of contact with said pressing rollers.

73. A device for handling tubular fabric, including a propelling head carrying longitu-

dinal and end rollers in relatively fixed relation adapted to lie inside a tube of traveling fabric, means for propelling the tubular fabric over said head, and a curved guiding member mounted on said propelling head and adapted to act in advance thereof to distend the tubular fabric preparatory to its passage onto said propelling head.

74. A device for handling tubular fabric, including a propelling head carrying longitudinal and end rollers in relatively fixed relation adapted to lie inside a tube of traveling fabric and engaging the inner surface of the fabric, rollers exterior of the tube of fabric co-operating with the rollers on said head to propel the fabric over said head and means carried by said propelling head for expanding the fabric preparatory to its passage onto said propelling head and adapted to control the tension of the fabric while propelled by said propelling head.

75. A device for handling tubular fabric, comprising means adapted to lie inside of a traveling tube of fabric, including a frame, longitudinal rollers thereon for engaging the fabric, end rollers projecting from said frame to engage the fabric, gears for transmitting the motion of said longitudinal rollers to said end rollers, whereby the end rollers are operated at a greater peripheral speed than the longitudinal rollers, and revolvable means exterior of the fabric and co-operating with said longitudinal rollers for propelling the fabric.

76. In a device of the class described, a propelling head adapted to lie inside a tube of traveling fabric, means outside the tubular fabric for exerting rolling pressure thereon to hold the propelling head stationary and to propel the fabric thereover, said propelling head including a telescoping frame composed of sections adapted to be expanded and contracted and means adapted to be operated exteriorly of the tubular fabric to adjust the propelling head whereby it is adapted for fabrics of different sizes.

77. In a device of the class described, a propelling head adapted to lie inside a tube of traveling fabric, means outside the tubular fabric for exerting rolling pressure thereon to hold the propelling head stationary and to propel the fabric thereover, said propelling head including a telescoping frame composed of sections adapted to be extended and contracted and means adapted to be operated exteriorly of the tubular fabric while the fabric is traveling over the head to adjust the frame of the propelling head and to adapt it for fabrics of different sizes.

78. In a device of the class described, a propelling head adapted to lie inside a tube of traveling fabric, means outside the tubular fabric for exerting rolling pressure thereon to hold the propelling head stationary and to propel the fabric thereover, said

propelling head including a telescoping frame composed of sections adapted to be expanded and contracted, means on said head tending to expand said frame and means adapted to be operated exteriorly of the fabric to contract said frame in opposition to said expanding means.

79. In a device of the class described, a propelling head adapted to lie inside a tube of traveling fabric, means outside the tubular fabric for exerting rolling pressure thereon to hold the propelling head stationary and to propel the fabric thereover, the propelling head including a telescoping frame composed of sections adapted to be expanded and contracted, springs on said head tending to expand the frame and means adapted to be operated exteriorly of the tubular fabric to contract the frame in opposition to the springs.

80. In a device of the class described, a propelling head adapted to lie inside a tube of traveling fabric, means outside the tubular fabric for exerting rolling pressure thereon to hold the propelling head stationary and to propel the fabric thereover, the propelling head including a telescoping frame composed of sections adapted to be expanded and contracted, and means including a roller adapted to be operated exteriorly of the tubular fabric to adjust the frame of the propelling head and to adapt it for fabrics of different sizes.

81. In a device of the class described, a propelling head adapted to lie inside a tube of traveling fabric, means outside the tubular fabric for exerting rolling pressure thereon to hold the propelling head stationary and to propel the fabric thereover, the propelling head including a telescoping frame composed of sections adapted to be expanded and contracted, said frame having rollers, springs tending to expand the frame, and means adapted to be operated exteriorly of the tubular fabric, and including a roller adapted to press on a roller of the propelling head in opposition to said spring whereby the frame of the propelling head is adjusted to accommodate fabrics of different sizes.

82. In a device of the class described, a propelling head adapted to lie inside a tube of traveling fabric, means outside the tubular fabric for exerting rolling pressure thereon to hold the propelling head stationary and to propel the fabric thereover, said propelling head including a telescoping frame composed of sections adapted to be expanded and contracted, spring means tending to expand said frame and means adapted to be operated exteriorly of the fabric and to apply opposing pressures to opposite sides of the frame in opposition to said spring means.

83. In a device of the class described, a propelling head adapted to lie inside a tube of

traveling fabric, means outside the tubular fabric for exerting rolling pressure thereon to hold the propelling head stationary and to propel the fabric thereover, said propelling head including a telescoping frame composed of sections adapted to be expanded and contracted, springs tending to expand said frame, and means for limiting the expansion, said last mentioned means being arranged exteriorly of the tubular fabric.

84. In a device of the class described, a propelling head adapted to lie inside a tube of traveling fabric, and comprising a head including a telescoping frame composed of sections adapted to be expanded and contracted laterally, said head having longitudinal rollers and having end rollers for engaging the sides of the fabric, rollers exterior of the fabric and co-operating with said longitudinal rollers to hold said head in position and to propel the fabric thereover, springs tending to expand said propelling head, and means exterior of the tubular fabric and co-operating with said end rollers through the fabric to contract said propelling head in opposition to said springs.

85. In a device of the class described, a propelling head adapted to lie inside a tube of traveling fabric, and comprising a head including a telescoping frame composed of sections adapted to be expanded and contracted laterally, said head having longitudinal rollers, and having end rollers for engaging the sides of the fabric, rollers exterior of the fabric and co-operating with said longitudinal rollers to hold said head in position to propel the fabric thereover, springs tending to expand said propelling head, means exterior of the tubular fabric and co-operating with said end rollers through the fabric to contract said propelling head in opposition to said springs and including rollers adapted to press the fabric against said end rollers of the propelling head.

86. In a device of the class described, a propelling head adapted to lie inside a tube of traveling fabric including a telescoping frame composed of sections adapted to be expanded and contracted, spring means for expanding said frame, means for propelling the fabric over said head by rolling interior and exterior pressures including end rollers on said head and means outside the tubular fabric for exerting contracting pressure on said head including rollers engaging the end rollers of said head through the fabric and means for simultaneously moving said latter rollers in opposite directions to press said head.

87. In a device of the class described, a propelling head adapted to lie inside a tube of traveling fabric, including a frame adapted to be expanded and contracted, spring means tending to expand said frame, longitudinal rollers on said head composed of sections

adapted to be moved axially toward and from each other with the adjustment of said frame, rollers exterior of the fabric and co-operating with said longitudinal rollers to hold said head and to propel the fabric thereover, and means exterior of the fabric and acting on said head to contract it in opposition to said spring means.

88. In a device of the class described, a propelling head adapted to lie inside a tube of traveling fabric, including a frame, longitudinal rollers thereon composed of sections adapted to move axially toward and from each other, a bearing member disposed between the sections of said rollers and having shafts on which the adjacent ends of said roller sections slidably engage, and spring means acting in opposition on said bearing member to maintain the latter centrally during longitudinal shifting of said roller sections.

89. In a device of the class described, a propelling head adapted to lie inside a tube of traveling fabric, including a frame composed of sections adapted to be expanded and contracted, longitudinal rollers on said head, composed of sections adapted to be moved axially toward and from each other, a bearing member interposed between the sections of said rollers and having shafts slidably engaged by the adjacent ends of said rollers, spring means acting in opposition against said bearing member to maintain the same centrally located in relation to said roller sections, and tending to expand said frame, and means exterior of the fabric for applying compression action to said head in opposition to said spring means.

90. In a device of the class described, a propelling head adapted to lie inside a tube of traveling fabric, including a frame composed of sections adapted to be expanded and contracted, longitudinal rollers on said frame composed of sections adapted to be axially moved toward and from each other, an intermediate bearing member between the roller sections having shafts for the adjacent ends of said roller sections, said bearing member having tubular guides projecting in opposite directions therefrom, said frame members having rods projecting into said tubular guides, springs in said tubes surrounding said rods and adapted to apply opposing pressures to said bearing member.

91. In a device of the class described, a propelling head adapted to lie inside a tube of traveling fabric, including a frame composed of sections adapted to be expanded and contracted, longitudinal rollers on said frame composed of sections adapted to be axially moved toward and from each other, an intermediate bearing member between the roller sections, having shafts for the adjacent ends of said roller sections, said bearing member having tubular guides projecting in

opposite directions therefrom, said frame members having rods projecting into said tubular guides, springs in said tubular guides surrounding said rods and adapted to apply 5 opposing pressures to said bearing member, and means for limiting the expansion of said frame to prevent said rods disengaging from said tubular guides.

92. In a device of the class described, a 10 propelling head adapted to lie inside a tube of traveling fabric, means outside the tubular fabric for exerting rolling pressure thereon to propel the fabric over said head, said propelling head including a telescoping frame 15 composed of sections adapted to be expanded and contracted, and spring means for exerting an expanding pressure on said frame members.

93. In a device of the class described, a 20 propelling head adapted to lie inside a tube of traveling fabric, and comprising a frame composed of sections adapted to be expanded and contracted, spring means tending to expand said frame, longitudinal rollers on said 25 frame composed of sections adapted to be moved axially toward and from each other with the expansion and contraction of said frame, and rollers exterior of the fabric co-operating with said first rollers to propel the 30 fabric over said head.

94. A device for handling tubular fabric, including means adapted to lie inside of a tube of traveling fabric and including a longitudinally extensible frame comprising relatively 35 movable sections each having revolvable members thereon extending transversely of the tubular fabric, and revolvable means exterior of the tubular fabric co-operating with the revolving members inside the tubular fabric for supporting said interior means 40 and propelling the fabric thereover, the frame of said interior means being adapted to be expanded and contracted to adapt said device for stretching the fabric to different 45 sizes.

95. A device for handling tubular fabric, including means adapted to lie inside a tube of traveling fabric and including a longitudinally extensible frame comprising relatively 50 movable sections, each having a plurality of spaced, revolvable members extending transversely of the tubular fabric, said frame being adapted to be expanded and contracted to adapt the device for stretching fabric to different sizes, and revolvable means exterior of the tubular fabric co-operating with the revolvable members inside the tubular fabric for supporting said interior means 55 and propelling the fabric thereover.

96. A device for handling tubular fabric, including means adapted to lie inside of a tube of traveling fabric and including a longitudinally extensible frame comprising relatively 60 movable sections adapted to be expanded and contracted to adapt the device

for stretching fabric to different sizes and each section having revolvable members thereon extending transversely of the tubular fabric and revolvable means exterior of the tubular fabric co-operating to engage the fabric between the exterior and interior revolvable members, said interior revolvable members being operated by rolling action by 70 said exterior revolving means.

97. A device for handling tubular fabric, 75 including a longitudinally extensible frame comprising relatively movable sections adapted to lie inside a tube of traveling fabric, said frame being adapted to be expanded and contracted to adapt the device for stretching fabric to different sizes, parallel, revolvable rollers on each section of said frame extending transversely of the tubular fabric and over which the fabric is adapted to travel, and means exterior of the tubular fabric including a roller lying between and co-operating with said interior rollers to drive the latter and to prevent the travel of the interior means with the fabric, said exterior rollers lying parallel with said interior rollers. 80

98. A device for handling tubular fabric including means adapted to lie inside a tube of traveling fabric, including a longitudinally extensible frame comprising relatively 85 movable sections, longitudinal rollers on each section of said frame extending transversely of the tubular fabric, end rollers on said frame, and means exterior of the tubular fabric co-operating with said longitudinal 90 rollers to propel the fabric over said interior device, said frame being adapted to be expanded and contracted to adapt the device for stretching fabric to different sizes. 95

99. A device for handling tubular fabric, 100 including means adapted to lie inside a tube of traveling fabric, including a longitudinally extensible frame composed of expanding and contracting members, longitudinal rollers thereon extending transversely of the tubular fabric, end rollers on said frame disposed at right angles to said longitudinal 105 rollers and adapted to be moved toward and from each other upon the adjustment of said frame, and means exterior of the tubular fabric and co-operating with said longitudinal 110 rollers to propel the fabric over said interior means. 115

100. A device for handling tubular fabric, 120 including a frame adapted to lie inside a tube of traveling fabric, said frame consisting of expanding and contracting sections, longitudinal rollers on said frame, end rollers on said frame disposed at right angles and in relatively fixed relation to said longitudinal rollers and means whereby said end rollers are driven by said longitudinal rollers, said end rollers being adapted to move toward and from each other with the frame sections, and revolvable means ex- 125 130
